UNITED STATES PATENT OFFICE.

ROBERT M. COLEMAN, OF HIGDEN, ARKANSAS.

BIVALVE-CATCHER.

1,052,652.

Specification of Letters Patent. Patented Feb. 11, 1913.

Application filed September 20, 1912. Serial No. 721,451.

To all whom it may concern:

Be it known that I, ROBERT M. COLEMAN, a citizen of the United States, residing at Higden, in the county of Cleburne and State 6 of Arkansas, have invented new and useful Improvements in Bivalve-Catchers, of which the following is a specification.

This invention relates to bivalve catchers and the object of the invention is to provide 10 a simple, efficient and durable device which may be operated in such a manner that it does not have to be removed from the water at each operation, but may be operated a number of times until all of the catcher 15 tines, or substantially all of them, have a bivalve attached thereto.

The invention embodies a plurality of 20 slidably mounted catching tines having pointed flesh-pricking ends adapted to enter the shell and cause the bivalve to close thereon so that it may be lifted from its bed.

A further object of the invention is the provision of a device of this character having 25 a rudder removably secured thereto so that, when in use, the frame or device will be prevented from turning or twisting in the water.

Further objects of the invention will appear 30 as the following specific description is read in connection with the accompanying drawings, which form a part of this application, and in which:—

Figure 1 is a side elevation. Fig. 2 is a 35 top plan view. Fig. 3 is a detail vertical sectional view. Fig. 4 is a section on the line 4—4 of Fig. 1. Fig. 5 is an enlarged perspective view of one of the tines removed from the frame.

Referring more particularly to the drawings, 1 represents a plurality of flat hoops or bands which are connected together by the diagonally extending cross pieces 2 riveted to the bands or hoops and are connected in the center by a supporting rod 3. The 40 outer ends of the braces 2 have their outer ends turned vertically at right angles to the bodies thereof to provide bracing extensions 4 which are connected to the supporting rod 3 by converging links 5 apertured to receive the rod 3 and held in position thereon at 45 their upper ends by a limiting collar 6 and a clamp nut 7 threaded upon the end of the rod 3. A ring 8 is swiveled to the end of the rod 3 so as to receive a connecting rope 9 50 which is provided for lowering and raising

the device. The upper ends of the bracing extensions 4 have secured thereto diagonal braces 10, which extend from the members 4 to the cross pieces 2.

Each one of the hoops or flat bands is provided with a plurality of holes separated about an inch apart and slidably mounted in these holes are the tine members 11 having their upper ends provided with loops 12 which limit the downward movement of the 65 tines. Intermediate their length the tines are provided with coils 13 which form weights and also limiting stops for preventing the penetrating points 14 from entering the shell too far and possibly killing the bivalve. Each penetrating point is sharpened, 70 as shown at 15, and in rear of the sharpened point the point is provided with an annular notch 16 which, when the shell is clamped upon the point, prevents removal of the 75 same.

If necessary, a rudder, such as is shown at 17, may be employed and if necessary may be removably attached to the frame by wrapping one end thereof around the supporting 80 rod 3 and the opposite end partially around one of the bracing extensions 4 and bending the end or prong formed on the rudder over the hook 18 which is formed on one of the links 5 which passes through the bracing extension 4.

In the operation of the device the frame is lowered to a point immediately over the bivalve bed where the bivalves are feeding with their shells open. The rope is then 90 suddenly released, thus permitting the frame and tines to drop rapidly upon the bed. Certain of the penetrating points will enter the open shells of the bivalves and prick the flesh of the bivalve, causing it to close upon 95 the penetrating prong. The frame is then lifted slowly until the bivalves caught upon the tines have been withdrawn from their bed and the frame is shifted in either direction and dropped again. This operation is 100 repeated until it is practically certain that all of the tines have bivalves thereon. The machine is then lifted out of the water and the bivalves forcibly removed therefrom. Those tines having bivalves thereon when 105 the device is dropped a second time will rise through the holes in the hoops in the same manner that the tines arise when engaging a stone or a raised hard surface on the bottom.

Having thus described the invention, what is claimed, is:—

1. A device of the class described comprising a frame, means for raising and lowering the same, and a plurality of entering tines slidably mounted thereon.
2. A device of the class described comprising a frame, means for raising and lowering the same, and a plurality of weighted entering tines slidably mounted therein.
3. A device of the class described comprising a frame, means for raising and lowering the same, a plurality of weighted entering tines slidably mounted therein, and a rudder carried by the frame for preventing the same from turning in swift water.
4. A bivalve catching device comprising a frame, means for raising and lowering the
- same, a plurality of pointed entering tines slidably mounted in the frame, and weighted and limiting coils formed in the length of the tines.
5. A bivalve catching device comprising a frame, a plurality of pointed entering tines slidably mounted therein, said tines having retaining notches formed adjacent their pointed ends, and weighted and limiting coils formed in their lengths, and a rudder carried by the frame for preventing the same from turning in swift water.

In testimony whereof I affix my signature in presence of two witnesses.

ROBERT M. COLEMAN.
